Primary Examiner — George D Kirschbaum*Assistant Examiner* — Natasha Vujcic(74) *Attorney, Agent, or Firm* — Leydig, Voit & Mayer, Ltd.**CLAIM**

The ornamental design for an LED lamp, as shown and described.

DESCRIPTION

FIG. 1 is a top right front perspective view of an embodiment of the LED lamp showing my new design;

FIG. 2 is a top plan view thereof;

FIG. 3 is a front elevational view thereof;

FIG. 4 is a rear elevational view thereof;

FIG. 5 is a left side elevational view thereof, the right side elevational view being a mirror image thereof; and,

FIG. 6 is a bottom plan view thereof.

The broken lines in the drawings illustrate portions of the LED Lamp, which forms no part of the claimed design.

1 Claim, 6 Drawing Sheets(56)
